CLAIM

The ornamental design for a combined cover and connector for use with an inflation mechanism for athletic equipment, as shown and described.

DESCRIPTION

FIG. 1 is a side elevational view of a combined cover and connector for use with an inflation mechanism for athletic equipment showing my new design, the opposite side being identical;

FIG. 2 is a top plan view thereof;

FIG. 3 is a bottom plan view thereof;

FIG. 4 is a cross-sectional view thereof taken along line IV—IV in FIG. 2; and,

FIG. 5 is a front elevational view thereof, the rear elevational view being identical.

FIG. 1

FIG. 2

FIG. 3

FIG. 4

FIG. 5
